UNITED STATES PATENT OFFICE.

JOHN W. CARLETON AND GEORGE E. TRASK, OF NEW BRITAIN, CONNECTICUT, ASSIGNORS TO THE UNION MANUFACTURING COMPANY, OF NEW BRITAIN, CONNECTICUT.

PLANE.

SPECIFICATION forming part of Letters Patent No. 746,285, dated December 8, 1903.

Application filed August 1, 1903. Serial No. 167,897. (No model.)

To all whom it may concern:

Be it known that we, JOHN W. CARLETON and GEORGE E. TRASK, citizens of the United States, residing at New Britain, in the county of Hartford and State of Connecticut, have invented certain new and useful Improvements in Planes, of which the following is a specification.

Our invention relates to improvements in planes; and the objects of our improvement are simplicity and economy in construction and convenience and efficiency in operation.

In the accompanying drawings, Figure 1 is side elevation of our plane. Fig. 2 is a central longitudinal section of the same, partly in elevation. Fig. 3 is a plan view of the same with the holding-cap, cap-iron, and cutting-bit removed. Fig. 4 is a side elevation of the middle portion of the iron frame 20 of the stock. Fig. 5 is a side elevation of our plane when made with an iron stock without the wooden body. Fig. 6 is a sectional view of the same on the line $\alpha\alpha$ of Fig. 5 when viewed in the direction of the dart in the said Fig. 5, the cutter being removed. Fig. 7 is a sectional side elevation of the middle portion of the stock and the adjusting-levers. Figs. 8 and 9 are plan and reverse plan views, respectively, of the cutting-bit with attached cap-iron and adjusting-nut, the same being adapted for use in both of the constructions herein shown. Fig. 10 is a plan view of the holding-cap and its screw.

A designates the wooden body, and B the iron frame, the said two parts together forming the stock of the plane. If desired, the wooden body A of the stock may be provided with a metal sole 5; but this is not essential. The frame B has an end plate 6 at its forward end provided with a hole for receiving the holding-screw 7 and also with a seat for the knob 8, the said seat being centrally perforated to receive the screw 9, that serves the double function of securing the said knob in place and of assisting to secure the said frame to the wooden body of the stock. At the rear end of the plate 6 there is a cross-rib 10, and extending rearwardly from the ends of the said cross-rib at opposite sides of the stock are the two side pieces 11 of the iron

frame B, with the holding-lugs 12 on their confronting inner faces over the opening for the throat 13 of the stock. These side pieces 11 extend parallel to each other along the sides of the stock to a point in the rear of 55 the middle of the length of the stock and then turn inwardly toward each other to the handle-seat 14 on the rear plate 15, near the end of which is the hole for the holding-screw 16. An ordinary handle 22 is secured to the handle-seat 14 by the rod 17, which is screw-threaded at its ends, one end being screwed into the threaded boss 18 on said handle-seat, while the other end is provided with the holding-nut 19. 60

The rear plate 15 extends forwardly to the side wings 20 of the frog, into which the said plate merges. An opening 21 is left in the rear plate between the said side wings 20 and rearwardly thereof to near the handle 22. 70 The side wings 20 of the frog are connected together near their upper ends by a bridge 23. The inclined front faces of the two side wings of the frog and the adjacent part of the rear plate form a seat for the cutting-bit 75 in continuation of the inclined rear wall 24 of the throat of the stock. The side wings 20 of the frog are formed with a lug 25, Fig. 4, that extends below the base of the frame side pieces 11, and between these lugs we 80 pivot a hub 26, having a short lever-arm 27 for engaging a slot in some device connected with the cutting-bit 28 or its cap-iron 29. The said hub is also provided with a longer lever-arm 33, that extends rearwardly from 85 the hub for use as a handle in operating the said short lever-arm and cutting-bit for its endwise adjustment. Such levers of themselves, broadly speaking, are not of our invention. As shown, the short arm 27 of the 90 lever engages a slot 36, Fig. 9, in the head of the screw 30, Fig. 2, which is held in the ordinary longitudinal slot of the cutting-bit 28 by means of the nut 31, the head of the said screw being shouldered by slabbing off 95 on each side, as at 32, Fig. 2, so that the slabbed-off portion of the screw-head may enter the slot in the bit. On the upper face of the bridge 23 we pivot an ordinary laterally-adjusting lever 34. We secure the cut- 100

ting-bit in place by means of a holding-cap C, the lower end of which is inserted under the confronting holding-lugs 12, after which the parts are tightened by turning in the 5 holding-screw 35 at the upper end of the holding-cap C.

The stock B^a, as shown in Figs. 5, 6, and 7, is wholly of iron and quite closely resembles the iron frame B, before described, only 10 it is not adapted to have a wooden body secured thereto, and consequently its side pieces 11^a are extended parallel to each other for nearly the whole length of the stock. 15 These side pieces have on their inner faces the holding-lugs 12, before described. The side wings 20^a of the frog are substantially the same as before described, only they are proportionally longer as the height of the inclined rear wall 24^a of the throat 13 in the 20 iron stock is less than in the wooden body of the stock first described. Like the side wings first described, a bridge 23 is provided to connect their upper ends. While there is an open space between the side wings 20^a for 25 pivoting the hub 26 of the lever 27 33, the pivot of the said lever comes higher up on the wings, and the lugs, which in the first-described construction project downwardly below the base of the wings, are omitted. 30 The pivot-pin 37 for the hub 26 may for convenience of heading it pass through the side pieces 11^a as well as the wings 20^a. The cutting-bit and connected parts and both of the 35 adjusting-levers are the same as first described and have the same reference-numerals.

We claim as our invention—

1. In a plane, the frame of the stock having the side pieces 11, a frog between the said side pieces having the side wings with open 40 space between, and the bridge 23 connecting the upper corners of the said side wings, which bridge forms a support for the laterally-adjusting lever.

2. In a plane, the stock having the side pieces, a frog between the said side pieces having the side wings with open space between, a bridge connecting the upper ends of the said side wings and forming a support for a laterally-adjusting lever, and an adjusting-lever 45 consisting of a hub, short arm and longer operating-arm, the same being pivoted in the open space between the lower part of the said side wings and in front of the said bridge, with the body of said operating-arm working 50 between the said wings while its handle end extends under the said bridge beyond the said wings at the rear thereof.

3. The herein-described plane, comprising

the wooden body and iron frame of the stock, the said frame having the front and rear 60 plates, connecting side pieces, and the frog between the said side pieces having the side wings with open space between and bridge at their upper corners forming a support for the laterally-adjusting lever. 65

4. The herein-described plane, comprising the wooden body and iron frame of the stock, the said frame having the front and rear plates with knob and handle seats, side pieces connecting the said plates and the frog between the said side pieces, the said frog having the side wings with open space between, the inclined front faces of the said side wings and the adjacent part of the said rear plate forming a direct seat for the cutting-bit, 70 while the lower parts of the said side wings form a support for the longitudinally-adjusting lever. 75

5. The herein-described plane, comprising a wooden body and frame of the stock, the 80 said frame having front and rear plates, connecting side pieces with the confronting holding-lugs on their inner faces, a frog between the said side pieces having the side wings with open space between, a bridge at the upper corners of the said wings forming a support 85 for a laterally-adjusting lever, and lugs at the lower corners of the said wings for the longitudinally-adjusting lever.

6. In a plane, the stock having side pieces, 90 a frog between the said side pieces composed mainly of a pair of inclined side wings with open space between, and a connecting-bridge 23, at the upper ends of the said side wings that spans the said open space between 95 them, the said side pieces forming a support for the longitudinally-adjusting lever and the said bridge forming a support for the laterally-adjusting lever, substantially as described. 100

7. In a plane, the stock having side pieces, a frog between the side pieces having the side wings with open space between, a longitudinally-adjusting lever with its long and short arms pivoted between the said side 105 wings with the upper end of the said long arm projecting rearwardly from the space between the said side wings, a bridge connecting the upper ends of the said side wings, and a laterally-adjusting lever pivoted on the said 110 bridge.
